UNITED STATES PATENT OFFICE.

MAXWELL VIDAVER AND ROBERT W. VIDAVER, OF NEW YORK, N. Y.

TOY CARTRIDGE.

1,284,497.

Specification of Letters Patent. Patented Nov. 12, 1918.

Application filed April 8, 1918. Serial No. 227,247.

To all whom it may concern:

Be it known that we, MAXWELL VIDAVER and ROBERT W. VIDAVER, citizens of the United States, and residents of the city of 5 New York, in the county of New York and State of New York, have invented certain new and useful Improvements in Toy Cartridges, of which the following is a specification.

10 The present invention relates to a cartridge, and more particularly to one that is adapted to be used in connection with toy guns.

From toy guns the projectiles are usually 15 expelled or thrown by compressed air or by springs. The means for compressing the air and the springs, respectively, are very complicated, and, if they get out of order, render the gun worthless since they 20 form parts of the gun.

The main object of the present invention is to provide a toy cartridge embodying the projectile expelling means, said expelling means being of the non-explosive type so as 25 not to be dangerous to the child playing with the same.

Another object of the invention is to devise a cartridge of the type mentioned which is simple in construction, efficient in 30 operation, and which can be manufactured on a commercial scale or, in other words, one which is so simple to make as not to be beyond the reasonable cost of such an article.

35 With these and other objects in view, which will more fully appear as the nature of the invention is better understood, the same consists in the combination, arrangement, and construction of parts hereinafter 40 described, pointed out in the appended claims and illustrated in the accompanying drawings, it being understood that many changes may be made in the size and proportion of the several parts and details of 45 construction within the scope of the appended claims without departing from the spirit or sacrificing any of the advantages of the invention.

One of the many possible embodiments of 50 the invention is illustrated in the accompanying drawings, in which:—

Figure 1 is a perspective view of a cartridge constructed in accordance with the present invention; Fig. 2 is a longitudinal 55 central section taken through the same; Fig. 3 is a section taken on line 3—3 of Fig.

2, on a larger scale; Fig. 4 is a section taken on line 4—4 of Fig. 2, also on a larger scale; and Fig. 5 is a perspective view of the projectile or bullet forming part of the cartridge. 60

In the drawings, the numeral 10 indicates the shell of the cartridge, the said shell being cylindrical and provided with a head 11 of substantial thickness. The head is, 65 preferably, provided with an ejecting rim 12, for the well-known purpose. In the outer face of the head is formed a recess 13, from which leads an aperture 14 to the interior of the shell. Through this aperture 70 and recess extends slidably an operating pin 15, provided upon its outer end with a head 16. A spring 17 bears against the head 16 and the shell head 11, said spring being disposed within the recess 13. To prevent this 75 spring from disengaging the operating pin 15 from the shell, any suitable stop may be provided, for instance a pin 18, that extends through the operating pin 15 and abuts against the inner face of the shell 80 head. The pin 15 bears against a holding member 19, preferably made of spring wire, that is in any suitable manner attached to the shell head and extends within the same toward the open end of the shell at an angle 85 to the longitudinal axis thereof. The free end of the holding member is provided with a lug 20, adapted to engage an interior annular shoulder 21 upon a projectile or bullet 22. The bullet is preferably cylindrical 90 and has a conoidal point 23. The shoulder 21 is formed within a recess 24 in the bullet, the end of said recess being conical, as clearly shown at 25. Between the head 11 of the shell and the bullet is interposed a heavy 95 helical expelling spring 26, one end of which is secured at 27 to the inner face of the shell head 11.

The operation of this device is as follows: 100 The cartridge is inserted into the gun in its assembled condition, shown in Figs. 1 and 2 of the drawings. When the elements are in these positions, the expelling spring 26 is compressed, the holding member 19 retaining the bullet in the shell against the action 105 of the said spring. To expel the projectile, the operating pin 15 is shifted inward, for instance by a "firing" pin coöoperating with the trigger of the gun. The operating pin thereby causes a disengagement of the lug 110 20 of the holding member from the shoulder 21 of the projectile. The ejecting spring

26 thus becomes operative, throwing the projectile. The spring 26 remains within the shell, as it is secured to the head 11. When the "firing" pin is disengaged from the head 16 of the operating pin, the spring 17 returns the said pin to its operative position. The shell is then withdrawn from the gun and a bullet inserted into the same. As a bullet is being inserted, the conical portion 10 25 of the recess in the shell causes the free end of the holding member 19 to move toward the longitudinal axis of the shell, its lug 20 engaging, due to the resiliency of the said holding member, the shoulder 21 of the 15 bullet, when the latter is forced, against the action of the spring 26, sufficiently into the shell.

From the foregoing it appears that the loading of the gun, expelling the bullet and 20 the extracting of the empty shell are the same as in any ordinary rifle or shot gun, yet the child incurs no danger by reason of the fact that the bullet expelling medium is a simple spring. The fact, that the loading, "firing" and extracting operations are 25 the same as in ordinary rifles or shot-guns, adds considerably to the attractiveness of the toy.

The device is simple in construction, inexpensive to manufacture and efficient in operation. There is nothing liable to get out of order in the cartridge, in contradistinction to the compressed air or spring operated guns.

35 What we claim is:—

1. A toy cartridge comprising a cartridge case, a projectile partly therein, an expelling spring within said cartridge case bearing against the latter and said projectile, means 40 for holding said projectile in said cartridge case against the action of said spring, and means extending through said cartridge case

for rendering, at will, said holding means inoperative.

2. A toy cartridge comprising a cartridge 45 case, a projectile partly therein, an expelling spring within said cartridge case bearing against the latter and said projectile, a resilient member on said cartridge case for holding said projectile in said cartridge case 50 against the action of said spring, and a pin extending through said cartridge case bearing against said resilient member for rendering the latter, at will, inoperative.

3. A toy cartridge comprising a cartridge 55 case, a projectile partly therein provided with an interior shoulder, an expelling spring within said cartridge case bearing against the latter and said projectile, a resilient member on said cartridge case having 60 a lug engaging said shoulder thereby holding said projectile in said cartridge case against the action of said spring, and a pin extending through said cartridge case bearing 65 against said resilient member for disengaging, at will, said lug from said shoulder.

4. A toy cartridge comprising a cartridge case, a projectile partly therein provided with an interior shoulder, an expelling spring within said cartridge case bearing 70 against the latter and said projectile, a resilient member on said cartridge case having a lug engaging said shoulder thereby holding said projectile in said cartridge case against the action of said spring, and a 75 shiftable pin on said cartridge case extending through the latter and bearing against said resilient member for disengaging, at will, said lug from said shoulder.

Signed at New York, in the county of 80 New York, and State of New York, this 6th day of April, A. D. 1918.

MAXWELL VIDAVER.
ROBERT W. VIDAVER.
